UNITED STATES PATENT OFFICE.

SAMUEL MAGED, OF DETROIT, MICHIGAN.

INDICATOR.

Application filed August 29, 1925. Serial No. 53,250.

To all whom it may concern:

Be it known that I, SAMUEL MAGED, a citizen of the United States, residing at Detroit, in the county of Wayne and State of Michigan, have invented a new and useful Improvement in Indicators, of which the following is a specification.

My invention relates to improvements in indicators, and refers more particularly to indicators to be attached to a wall of a vehicle for exhibiting the name of the street or station at which the next stop may be or will be made.

The invention aims to provide an indicator that can be cheaply produced, and at the same time is both durable and positive in action. It consists in certain novel construction and combination of parts hereinafter more fully described with the aid of the accompanying drawings and claimed.

In the drawings:

Figure 1 illustrates a front view of the indicator partly in elevation and partly in section.

Figure 2 is a section on the line 2—2 of Figure 1.

Figure 3 is a section on the line 3—3 of Figure 1.

Figure 4 shows a detail, and

Figure 5 is a section on the line 5—5 of Figure 4.

Referring more particularly to the drawings, 1 designates a casing provided in the front with a substantially centrally located opening 34, and, if desired, side openings 35. Above the opening 34 on the casing I usually write the words "The next street is" or other suitable words.

In the casing runways 2 are mounted as by braces 3 and 4. The runways are provided with outwardly extending flanges 5 on their outer edges. 6 indicates an endless carrier which consists of a plurality of plates 7 both sides of which are pivotally connected to the adjacent plates by means of hinge pins 8, and the outer faces of the plates have receiving grooves 9 adapted to receive name plates 10, and, when desired, advertising plates 11. Lugs 12 are provided at each end of the plates 7 to which the members 13 are secured. Each of the latter forms a spindle for its roller 14 and its outer end also acts as a contact member as will be mentioned hereinafter. The flanges of the runways 2 and the sides of the lugs 12 limit the lateral movement of the rollers 14.

On both sides of the casing lateral projections 15 are provided, in each of which there is a magnet 16 or 16^a and a plate 17 or 17^a. The latter are mounted on levers 18 and 18^a respectively which are pivotally attached to the casing at 19 and 19^a, and springs 20 and 20^a extend from the outer ends 21 and 21^a of the lever to the casing in such a manner as to tend to draw their plates 17 and 17^a away from the magnets. Stops 37 and 37^a, which are secured to the lateral projections, limit the distance of the plates 17 and 17^a from the magnets 16 and 16^a. At the opposite ends 22 and 22^a of the levers feed fingers 23 and 23^a are pivotally arranged and have arms 24 and 24^a so connected by springs 25 and 25^a to the levers 18 and 18^a that the back of the arms 24 and 24^a will normally rest against the stops 26 and 26^a integral with the levers. Sprockets 27 and 27^a are also rotatably mounted in the lateral projections 15, and are so positioned that each will contact with the members 13 on its side of the casing, and are adapted to be actuated by the feed fingers 23 and 23^a.

Referring now to the electrical circuits, the source of energy 28 is connected on one side by leads 29 and 30 to the magnets 16 and 16^a respectively, and on the other side to one terminal 31 of a two-way switch. A second terminal 32 of the latter is connected to the magnet 16, and a third terminal 33 of the two-way switch is wired to the magnet 16^a.

When contact is made between the terminals 31 and 32 the magnet 16 is energized and the lever 18 is drawn downwards so that the feed finger 23 strikes one of the teeth of the sprocket 27 and causes the latter to turn. The opposite tooth of the sprocket then strikes one of the members 13 on that side of the indicator and forces it upwards causing the endless carrier 6 to move upwards until the plate immediately below the one previously exhibited through the slot 34 is brought into view. Meanwhile as the normal position of both the feed fingers 23 and 23^a is such as to be just clear of the circular path of the teeth of the sprockets 27 and 27^a which they are adapted to engage, as the sprocket 27^a on the opposite side of the casing is turned by the adjacent members 13 it rotates just clear of the feed finger 23^a. When connection between the contacts 31 and 32 is broken, the spring 20 causes the lever 18 to reassume its normal

position. In moving back the upper side of the feed finger 23 strikes the next tooth of the sprocket to the one on which it has just exerted downward pressure and swings 5 downwards about its pivotal point 40 on the lever 18 until just before the latter reaches its maximum height above the magnet 16 by which time the feed finger is sufficiently far above the tooth of the sprocket 10 to be released therefrom. As soon as that occurs the spring 25 pulls the feed finger back to its normal position against the stop 26 and it is in position for its next stroke. The spring 25 must be weak enough to allow 15 the feed finger to swing downwards without turning the sprocket in the reverse direction on its return stroke.

Similarly by connecting the contacts 31 and 33 the feed finger 23^a moves the sprocket 20 27^a and turns the endless carrier 6 downwards.

While in the foregoing the preferred embodiment of the invention has been described and shown it is understood that the construction is susceptible to such alterations as fall within the scope of the appended claims.

What I claim as my invention and desire to secure by Letters Patent is:—

30 1. In an indicator, the combination of a casing, endless runways mounted in said casing, an endless carrier having projecting members on each side, rollers mounted on said members, said rollers being adapted 35 to move along said runways, a lateral projection on each side of said casing, a sprocket mounted in each projection, said sprockets being adapted to engage said members and move the carrier round the runway, and 40 means for turning the sprockets.

2. In an indicator, the combination as de-

scribed in claim 1, wherein one of the sprockets is adapted to move the carrier in one direction, and the other sprocket is adapted to move the carrier in the opposite direction. 45

3. In an indicator, the combination as described in claim 1, wherein a lever actuated by a magnet is mounted in each lateral projection and is adapted to strike a tooth of the sprocket within that projection and cause it to turn, and wherein spring means are provided for returning the levers to normal position. 50

4. In an indicator, the combination of a casing having an opening therein, endless runways mounted in said casing, a plurality of plates pivotally connected to one another transversely of their length, a nameplate receiving groove on each of said plates, 60 a projecting member on each end of said plates, a roller mounted on each of said projecting members and adapted to move along the runways, a lateral projection on each side of the casing, a sprocket wheel 65 rotatably mounted in each lateral projection, each sprocket being adapted to contact the projecting members on one side of the plates and to cause said plates to move round said runway, and means for rotating said 70 sprockets.

5. In an indicator, the combination as described in claim 4 wherein a magnet is provided in each projection, a lever having a plate thereon in each projection, spring 75 means for tending to hold said levers and plates in spaced relation from said magnets, pivotal fingers on said levers, and spring means for tending to hold said feed fingers in operating position.

SAMUEL MAGED.
